Francis H. Good,
BY
Diedersheim & Fairbank

ATTORNEYS:

UNITED STATES PATENT OFFICE.

FRANCIS H. GOOD, OF PHILADELPHIA, PENNSYLVANIA.

CARPET-CLEANER.

SPECIFICATION forming part of Letters Patent No. 600,525, dated March 15, 1898.

Application filed June 17, 1897. Serial No. 641,142. (No model.)

To all whom it may concern.

Be it known that I, FRANCIS H. GOOD, a citizen of the United States, residing in the city and county of Philadelphia, State of Pennsylvania, have invented a new and useful Improvement in Carpet-Cleaning Machines, which improvement is fully set forth in the following specification and accompanying drawings.

10 My invention consists of an improvement in machines for beating carpet, &c., whereby the work is easily and effectively accomplished with little liability to injure the carpet.

It further consists of novel details of construction, all as will be hereinafter set forth.

Figure 1 represents a side elevation of a carpet-beating machine embodying my invention, showing the housing thereof in section. Fig. 2 represents an end elevation thereof 20 with a portion of the casing broken away and with the flooring upon which the machine rests shown in section. Figs. 3 and 4 represent perspective views of beaters and covering employed.

25 Similar letters of reference indicate corresponding parts in the figures.

Referring to the drawings, A designates the housing for the machine, the same having an opening therein which is provided with a door 30 or cover B, so that access may be had to the interior of the same.

C designates a shaft which is supported by a standard D and upon which are the loose and fixed pulleys E and F, and mounted on 35 said shaft are the cams G and H.

J and K designate shafts which are suitably mounted in said housing and are supported in ears L, attached to a beam M of the housing, which is further strengthened by 40 the bar or rod N, said shafts J and K being supported in substantially the same plane and having a small distance therebetween.

Mounted on the shaft K is a cam P, which is adapted to contact with the cam G when 45 the latter is operated, and each of the shafts J and K is provided with the partly-toothed gears Q and R, whose teeth mesh with each other.

S designates clips which are adjustably secured on the shaft J, a similar set of clips and

component parts being secured to the shaft K. The clips S carry the frames T, as many being employed as desired.

U designates beaters which are mounted on the frames T, and V designates corresponding beaters which are carried by a frame similar to T, which is mounted on the shaft K, it being noticed that the beaters on one frame alternate with those on the other, and in Fig. 1 for convenience I have shown the 55 beaters V as broken away to indicate that they are secured to another frame than T.

W designates torsional springs, one end of each of which is secured to a fixed point and the other end is secured to a collar A', which 60 is adjustably mounted on the shaft J and is provided with openings B' for the insertion of a tool in order to adjust the same, it being remembered that the shaft K is provided with similar springs and collars.

C' designates a lever which is suitably mounted and has secured thereto the bar D', which may be of any length, and is provided with a pawl E', which is adapted to engage the teeth on a ratchet F', the latter being 75 supported on the standard G', one end of said lever C' being adapted to be engaged by the cam H, and has a pin H' to limit the movement thereof, a spring J', secured to said bar D', being adapted to return the parts to 80 the proper position.

The ratchet F' is mounted on a shaft K', upon which is a roller L', the same carrying the endless belt M', which passes around the roller N', the latter being supported on a 85 standard P'.

Q' designates brackets mounted on the housing A, which act as journals for the roller R', to which is secured the apron S', and being provided with the crank-handle T'.

U' designates a roller suitably mounted at a point substantially in line with the space between said shaft J and K.

The casing A is provided with an opening V' to admit the passage of the carpet, and 95 an opening W' in the flooring A' is also made to allow the carpet to pass therethrough.

B' designates an exhaust-fan situated in an opening in the casing A, which is adapted to conduct the dust and dirt to a desired point. 100

An opening C^2 is also provided in the casting to allow the passage of the apron S' and the carpet D^2 .

The beaters may be made of a flexible rod 5 which, if desired, may be covered by a rubber tube E^2 . (Seen in Fig. 3, dotted lines.)

The operation is as follows: The apron S' is first unwound from the roller R' and is brought through the opening C^2 in the casting 10 and then between the shafts J and K and thus between the beaters U and V and is then carried beneath the roller U' . The carpet D^2 is passed through the opening V' in the casing and is stitched or otherwise secured 15 to the apron S' , which can now be rewound upon the roller R' by operating the crank T' until the carpet is between the beaters U and V . The shaft C is now operated by placing a belt on the fixed pulley F . As the shaft C 20 revolves it carries with it the cams G and H . The said cam G contacts with the cam P , which is secured to the shaft K , and causes the same to revolve, as indicated by the arrow in Fig. 2, and with it the gear Q , which, meshing with the gear R of the shaft J , causes the same to revolve in the opposite direction, or as indicated by the arrow in Fig. 2, so that the beaters U and V will be moved in the directions indicated in dotted lines in Fig. 2— 25 that is, opposite to each other—and after the cam G has passed the cam P the shafts will return to their former position by means of the torsional springs W , thus causing said beaters to strike the carpet and remove the 30 dust and dirt. The cam H is meanwhile engaged with the lever C' , which will be moved in the direction indicated by the arrow in Fig. 2, and will cause the rod D' to move and draw with it the ratchet F' , which is mounted 35 upon the shaft K' , and cause the same to revolve and with it the pulley in the direction indicated by the arrow, it being noticed that the spring J' returns the rod D' to its former 40 position after the cam H has passed the lever C' . When the carpet D^2 has reached a sufficient height, the same is removed from the 45 apron S' and is placed over the endless belt M' and is engaged by said belt in any suitable and convenient manner. As the roller L' is 50 caused to revolve it moves the apron M' in the direction indicated by the arrow in Fig. 2, and after the carpet D^2 has been engaged by 55 said apron said carpet will be carried therewith, so that after each stroke of the beaters the carpet will move a certain distance, whereby an intermittent movement is accorded and the continuous beating upon the various parts is continued. The carpet D^2 is caused to 60 pass through the opening W' in the flooring and is received upon the lower floor after the 65 operation of beating has been accomplished, it being noticed that the fan B^2 has been meanwhile placed in operation and causes the dust and dirt to pass out and be carried to any desired point.

In the drawings I have shown two sets of double beaters; but it will of course be understood that I may apply or use as many as may be required, this only increasing the size of the machine.

If it should be found necessary in order to cause greater or less force to the beaters, the collar A' may be so adjusted upon the shafts J and K as to give additional or less power to the springs W , and thus force the beaters 70 against the carpet harder or easier, it thus being seen that the power of the blows can be gaged, as is often essential when the carpet is well worn and hard blows might cause tearing of the same.

It will be readily seen that but one set of beaters may be employed, if so desired.

I may desire to make further changes which may come within the scope of my invention, and I therefore do not wish to be limited to 85 the exact construction as herein shown and described.

Having thus described my invention, what I claim as new, and desire to secure by Letters Patent, is—

1. In a carpet-cleaning machine, a frame, oscillating shafts having meshing gearing and provided with beaters, a driving-shaft operating said oscillating shafts, feeding-rollers, and an endless belt with operating mechanism 90 actuated by the rotation of said driving-shaft.

2. In a machine for beating carpet, a frame, a power-shaft, cams thereon, a pair of shafts having gear meshing with each other, a cam on one of said shafts contacting with one of 100 said cams on said power-shaft, a lever adapted to contact with the other cam on said power-shaft and operating means for moving the carpet and beaters on said shafts.

3. In a carpet-beating machine, a frame, a power-shaft, a cam thereon, a set of shafts adapted to revolve in opposite directions, gears on said shafts meshing with each other, a cam on one of said shafts adapted to contact with a cam on said power-shaft and a set 105 of beaters mounted on each of said shafts, and carried thereby, whereby they will operate oppositely to each other.

4. In a carpet-beating machine, a frame, a power-shaft, a cam thereon, a set of shafts 115 adapted to operate in opposite directions, gears on said shafts meshing with each other, a cam on one of said shafts adapted to contact with a cam on said power-shaft, a set of beaters mounted on each of said shafts and carried thereby, and adjustable springs connected with said shafts and adapted to return the same to position.

5. In a carpet-beating machine, a frame, shafts journaled in said frame, beaters carried by said shafts, gears meshing with each other and mounted on said shafts, a cam on one of said shafts, a power-shaft, a cam on 120 said power-shaft adapted to connect with the cam on the shaft-carrying beaters, and an 125

intermittent feed mechanism for carrying a carpet through said machine between said beaters.

6. In a carpet-beating machine, a frame, shafts journaled in said frame, beaters carried by said shafts, gears meshing with each other and mounted on said shafts, a cam on one of said shafts, a power-shaft, a cam on said power-shaft and adapted to contact with

the cam on the shaft-carrying beaters, an endless belt for moving a carpet between said beaters, and an intermittently-operated mechanism for moving said belt. 10
